APPARATUS FOR REGULATING COMBUSTION IN SPREADER STOKER FURNACES

Earle C. Miller, Worcester, Mass., assignor to
 Riley Stoker Corporation, Worcester, Mass., a
 corporation of Massachusetts

Application February 20, 1948, Serial No. 9,899

5 Claims. (Cl. 110—101)

1

This invention relates to combustion regulation, and more particularly to an improved apparatus for regulating combustion in furnaces of the spreader stoker type.

The ordinary spreader-stoker furnace includes a mechanism which feeds fuel at a controlled rate to a rotor or distributor located adjacent an opening in a wall of the furnace. The distributor is rotated, usually about a horizontal axis, and it is provided with blades which throw the fuel through the wall opening and onto a grate within the furnace to maintain a bed of burning fuel. Air is supplied for combustion, and the finer particles of fuel burn in suspension, whereas the coarser particles fall upon the fuel bed and are there consumed.

Two general types of combustion control are in common use. First there is the so-called "floating" control, whereby the supplies of fuel and air are varied in a smooth or gradual manner in accordance with variations in the demand for heat, within a definite operating range. Second there is the so-called "start-stop" control, whereby the supplies of fuel and air are started and stopped in accordance with the variations in the demand for heat. Floating control provides more efficient operation, since the rate of combustion is maintained closely in step with the heat requirements, and sudden changes in combustion conditions are largely avoided. The operating range however is more limited, and it is difficult to operate with such a control when the demand for heat is very low. Start-stop control is well adapted for installations in which a very wide operating range is required, and in which the demand for heat may at times be at a minimum. However, the combustion efficiency will be less, because of the sudden changes in the combustion rate between zero and the maximum. Furthermore, it is not desirable to stop the rotation of the stoker distributor, for when this is done some of the fuel may become wedged between the distributor and its housing and thus prevent the distributor from starting its rotation again. Also, a stationary shaft will be heated from one side only, and this will cause distortion of the shaft.

It is accordingly one object of the invention to overcome these difficulties and to provide an apparatus for regulating combustion in a spreader stoker furnace which will realize the advantages of the known types of control while avoiding the disadvantages thereof.

It is a further object of the invention to provide an apparatus whereby combustion in a

2

spreader stoker furnace may be regulated in an efficient manner throughout a wide range of demand for heat.

It is a further object of the invention to provide an apparatus whereby the combustion in a spreader stoker furnace may be regulated automatically in a thoroughly satisfactory manner even when the demand for heat is very low.

With these and other objects in view, as will be apparent to those skilled in the art, the invention resides in the combination of parts set forth in the specification and covered by the claims appended hereto.

Referring to the drawings illustrating one embodiment of the invention, and in which like reference numerals indicate like parts, the single figure is a somewhat diagrammatic side elevation of a steam generating furnace fired by a spreader stoker and equipped with combustion regulating apparatus.

The embodiment illustrated comprises a furnace 10 having a front wall 11, a combustion chamber 12, a grate 14, and an ash pit or air chamber 15 beneath the grate. At the front of the furnace there is provided the usual fire door 16 immediately above the grate, and the usual ash door 17 communicating with the ash pit 15. A fuel admission opening 19 is provided in the wall 11 above the door 16. A spreader stoker 20 of known construction is mounted on the wall 11 to project fuel through the opening 19. This stoker comprises a distributor 22 rotatable about a horizontal axis adjacent the opening 19, a reciprocable ram 23 above the distributor to feed fuel thereto, and a hopper 24 in position to supply fuel by gravity to the ram. The distributor 22 and the ram 23 are both driven in known manner by an electric motor 26. The stoker also includes a pivotally mounted feed control arm 27 which can be moved to vary the stroke of the ram 23 in known manner between zero and a maximum. When the arm 27 is in the position indicated by the broken line 28 the stroke of the ram and the rate of feed will be zero, whereas when the arm is in the position indicated by the broken line 29 the stroke of the ram and the rate of feed will be at a maximum. The arm 27 is biased downwardly toward its lowermost or zero position by a weight 30. Air for combustion is supplied to the ash pit 15 through a duct 32 by means of a fan 33 driven by an electric motor 34. The air flow is controlled by a damper 36 located within the duct 32 and provided with an arm 37. This arm supports a weight 38 which

serves to bias the damper toward its closed position.

The heat produced by the combustion of the fuel is utilized to generate steam in a boiler 40 associated with the furnace 10. This boiler comprises the usual water tubes 41 located in the path of the hot gases leaving the combustion chamber 12, and the usual steam delivery pipe 42. Upon leaving the boiler, the furnace gases flow through a duct 44 to a stack or other draft producing device (not shown). Within the duct 44 there is provided a damper 45 having an arm 46. This damper is preferably controlled automatically in known manner to maintain a predetermined pressure, slightly below atmospheric, in the combustion chamber 12. For this purpose there is shown a regulator 48 of the type disclosed in the United States patent to Temple No. 1,992,048, granted February 19, 1935. This regulator comprises a pilot valve mechanism 49 supplied with a suitable fluid under pressure through a pipe 50 and connected by tubes 52 to a hydraulic motor 53. This motor is connected to the damper arm 46 by a rod 54. The regulator 48 is connected to the combustion chamber 12 by a pipe 55.

The fuel feed and the flow of combustion air are controlled automatically in accordance with variations in the demand for steam from the boiler 40. For this purpose there is provided an automatic regulator 57 of the type disclosed in the United States patent to Temple No. 2,049,549 granted August 4, 1936. This regulator comprises a diaphragm chamber 58 and a reversible motor 59. The diaphragm chamber 58 is connected by a pipe 61 to the steam delivery pipe 42, and the motor 59 is connected by a rod 62 to a lever 63. A flexible cable 65 leads from the lever 63 over an idler sheave 66 to the damper arm 37. A second flexible cable 68 leads from the lever 63 over an idler sheave 69, thence in the form of a loop beneath an idler sheave 70, and thence over idler sheaves 71 and 72 to the fuel feed control arm 27. The construction is such that with the idler sheave 70 in the position shown in full lines, a full stroke of the regulator 57 will move the arm 27 through the angle A between the broken line 29 and a broken line 73 which lies at an angle B with the broken line 28. The angle A is preferably considerably greater than the angle B. As the arm 27 is moved from the position 29 to the position 73, the damper 36 will be moved from an open position to a nearly closed position, maintaining the proper ratio between the supplies of fuel and air at all times. The automatic control throughout the angle A will take place in a smoothly graduated or floating manner, and it will correspond to a definite range of heat demand as indicated by the steam pressure transmitted through the pipe 61 to the regulator diaphragm chamber 58. Thus, by way of example, the maximum load position 29 may correspond to a steam pressure of say 200 pounds per square inch, and the position 73 may correspond to a steam pressure of say 208 pounds. While the steam pressure is at a value between these limits, the regulator 57 will hold the feed control arm 27 at a corresponding intermediate position.

If now the demand for heat should become so low as to cause the steam pressure to rise appreciably above 208 pounds (say to 210 pounds), requiring even less fuel than is represented by the arm position 73, a further regulating means

will assume control to stop the fuel feed and the fan 33. For this purpose certain additional regulating apparatus is provided. Thus the idler sheave 70 is mounted on a yoke 75 which may be moved vertically by a reversible hydraulic motor 76 connected by tubes 77 to a valve mechanism 79, the latter being supplied with a suitable fluid under pressure through a pipe 80. A solenoid 81 is connected to the valve mechanism 79 to actuate the same in a known manner, the arrangement being such that when the solenoid is energized, fluid will be admitted to the upper end of the motor 76 to hold the sheave 70 in its lower or full line position. Upon deenergization of the solenoid, the motor 76 will raise the sheave 70 to the broken line position, thus slackening the cable 68 sufficiently to lower the arm 27 to the zero feed line 28. A pressure actuated master controller, such as a master switch 83 of the well-known mercury tube type, is connected to the steam pressure pipe 61. This switch may be adjusted to open when the steam pressure increases to say 210 pounds, and to close when the steam pressure decreases to say 208 pounds. The fan motor 34 is connected to a suitable source 85 of electrical energy by means of a magnetic contactor having three normally open switches 86 and an actuating coil 87. There is also provided a magnetic contactor having two normally open switches 89 and 90, and an actuating coil 91. To ensure maintenance of fuel bed ignition during periods of low heat demand, an interval timer 93 is provided having a switch 94 which is closed at predetermined intervals by a small electric motor 95. In addition, a source 97 of electrical energy is provided, with a manually operable switch 98 to control the same.

The various electrical connections will now be described. The solenoid 81 and the switch 90 are connected in series across the source 97, as controlled by the switch 98. The pressure switch 83 and the coil 91 are likewise connected in series across the source 97, and the switch 89 and the coil 87 are similarly connected in series. The switch 94 is connected in parallel with the switch 90. The motor 95 is connected across the source 97, as controlled by the switch 98.

The operation of the invention will now be apparent from the above disclosure. The switch 98 will be closed, and if the steam pressure is less than 208 pounds the master pressure switch 83 will be closed, energizing the coil 91, so that the switches 89 and 90 will be closed. The closed switch 89 will energize the coil 87, so the switches 86 will be closed and the fan motor 34 will be in operation to drive the fan 33. The closed switch 90 will energize the solenoid 81, so that the valve 79 will cause the hydraulic motor 76 to hold the idler sheave 70 in its lower or full line position. The motor 95 of the interval timer 93 will close the switch 94 periodically, but this will have no effect so long as the switch 90 is closed. The stoker motor 26 will operate continuously, rotating the distributor 22 and reciprocating the ram 23 to feed fuel to the distributor from the hopper 24. The distributor will throw the fuel rearwardly through the opening 19 into the combustion chamber 12, where the fine particles will burn in suspension and the coarse particles will fall upon the grate 14 to form a bed of burning fuel. The hot combustion gases will generate steam in the boiler 40, and the gases will then escape at reduced temperature through the duct 44. The regulator 48 will control the damper 45 in known man-

ner to maintain a predetermined sub-atmospheric pressure in the combustion chamber 12. The steam will flow through the pipe 42 to a place of use. Any increase in the demand for steam will tend to reduce the steam pressure, and vice versa. So long as the steam pressure remains within the operating range of the regulator 57, which we have assumed to be from 200 to 208 pounds, this regulator will control the fuel feed control arm 27 and the air control damper 36 in a smooth or floating manner. In other words, these parts will assume positions varying with the steam pressure, the position of the arm 27 being somewhere between the lines 29 and 73.

If now the demand for steam decreases until the steam pressure rises to 208 pounds, the regulator motor 59 will be at the upper limit of its stroke, the damper 36 will be nearly closed, and the stoker arm 27 will be in the position indicated by the line 73, so that the ram 23 will feed fuel at a low rate to the distributor. If the steam pressure continues to increase and reaches 210 pounds, the master switch 83 will open, deenergizing the coil 91, and opening the switches 89 and 90. Opening the switch 89 will deenergize the coil 87 and thus open the switches 86, so that the motor 34 and the fan 33 will come to a stop. Opening the switch 90 will deenergize the solenoid 81, causing the valve 79 to admit pressure fluid to the lower end of the motor 76, and the sheave 70 will accordingly be raised to the broken line position. This will slacken the cable 68 and lower the arm 27 to the position indicated by the line 28, so that the stroke of the ram will be reduced substantially to zero. While the steam pressure remains above 208 pounds, the periodic closing of the switch 94 by the motor 95, say for two minutes out of every ten minutes, will energize the solenoid 81 and cause the sheave 70 to return to its full line position, moving the arm 27 to the line 73 position, and supplying a small amount of fuel to the grate 14. This will ensure the maintenance of ignition in the fuel bed during long periods of low demand for steam. When the steam pressure decreases to 208 pounds, the master switch 83 will close, energizing the coil 91, and closing the switches 89 and 90. The closed switch 89 will energize the coil 87, closing the switches 86 and starting the fan motor 34 and the fan 33. The closed switch 90 will energize the solenoid 81, causing the motor 76 to lower the sheave 70 and raise the fuel feed arm to the line 73 position. Thus the rate of combustion will be increased, tending to raise the steam pressure once more.

It will accordingly be seen that unless the demand for steam is very low, the combustion will be under the control of the regulator 57, and this regulator will operate in a floating manner to change the fuel and air supplies smoothly and gradually in accordance with variations in the steam pressure. Under conditions of very low demand for steam, the master switch 83 will be in control, starting and stopping the fuel feed and the forced draft fan as required to meet the steam requirements. Furthermore, if the demand for steam is low or even zero, the interval timer 93 will bring about an intermittent feed of fuel in amounts sufficient to maintain ignition in the fuel bed, the necessary air flowing past the nearly closed damper 36 by reason of the slight suction in the combustion chamber 12.

The invention makes it possible to operate the furnace automatically and efficiently over a very wide range of demand, in fact from zero demand

up to the maximum fuel burning capacity of the apparatus. Since the distributor 22 is rotated continuously, even under start-stop control, there is no danger of fuel particles becoming wedged between the distributor and its housing, or of the distributor shaft being distorted by the heat.

It will be clear that the angular movement A of the fuel feed control arm 27 corresponds to a relatively low range in steam pressure and to a relatively high range in demand for heat. Similarly, the angular movement B corresponds to a relatively high range in steam pressure and to a relatively low range in demand for heat.

Having thus described my invention, what I claim as new and desire to secure by Letters Patent is:

1. In combination with a furnace for the combustion of fuel and the production of heat, a rotatable spreader stoker distributor to supply fuel to the furnace, means to continuously rotate said distributor, means to feed fuel to the distributor, a forced draft fan to supply air to the furnace, a master controller responsive to changes in the demand for heat, and connections from the controller to the fuel feeding means and the fan effective to start and stop the fuel feed and the fan as the demand for heat increases and decreases and while the distributor continues to rotate.
2. In combination with a furnace for the combustion of fuel and the production of heat, a rotatable spreader stoker distributor to supply fuel to the furnace, means to continuously rotate said distributor, means to feed fuel to the distributor, a forced draft fan to supply air to the furnace, an air control damper operatively associated with the fan, a master controller responsive to changes in the demand for heat over a relatively low range, an automatic regulator responsive to changes in the demand for heat over a relatively high range, connections from the controller to the fuel feeding means and the fan effective to start and stop the fuel feed and the fan as the demand for heat increases and decreases within the low range and while the distributor continues to rotate, and connections from the regulator to the fuel feeding means and the damper effective to adjust the same as the demand for heat varies within the high range.
3. In combination with a furnace for the combustion of fuel and the generation of vapor, a rotatable spreader stoker distributor to supply fuel to the furnace, means to continuously rotate said distributor, means to feed fuel to the distributor, a forced draft fan to supply air to the furnace, an air control damper operatively associated with the fan, a master controller responsive to changes in the vapor pressure over a relatively high range, an automatic regulator responsive to changes in the vapor pressure over a relatively low range, connections from the controller to the fuel feeding means and the fan effective to start and stop the fuel feed and the fan as the vapor pressure decreases and increases within the high range and while the distributor continues to rotate, and connections from the regulator to the fuel feeding means and the damper effective to adjust the same as the vapor pressure varies within the low range.
4. In combination with a furnace for the combustion of fuel and the generation of vapor, a rotatable spreader stoker distributor to supply fuel to the furnace, means to continuously rotate said distributor, means to feed fuel to the distributor, a forced draft fan to supply air to the furnace,

an electric motor to drive the fan, an air control damper operatively associated with the fan, a master pressure switch responsive to changes in the vapor pressure over a relatively high range, a first reversible motor controlled by the switch and movable through a predetermined stroke, an automatic regulator responsive to changes in the vapor pressure over a relatively low range and including a second reversible motor movable through a predetermined stroke, connections from the second reversible motor to the damper to adjust the same, connections from the second reversible motor to the fuel feeding means to adjust the same between a high feeding position and a low feeding position, means connecting the first reversible motor to the last mentioned connections to adjust the fuel feeding means between the said low feeding position and a zero feeding position, and connections from the master pressure switch to the fan motor to start and stop the same as the vapor pressure reaches respectively the lower and upper limits of the said high range.

5. In combination with a furnace for the combustion of fuel and the production of heat, a 25 rotatable spreader stoker distributor to supply fuel to the furnace, means to continuously rotate

said distributor, means to feed fuel to the distributor, a master controller responsive to changes in the demand for heat over a relatively low range, an automatic regulator responsive to changes in the demand for heat over a relatively high range, connections from the controller to the fuel feeding means effective to start and stop the fuel feed as the demand for heat increases and decreases within the low range and while the distributor continues to rotate, and connections from the regulator to the fuel feeding means effective to adjust the fuel feed as the demand for heat varies within the high range.
